UNITED STATES PATENT OFFICE.

ERNEST BRAMMER, OF VICTORIA, BRITISH COLUMBIA, CANADA.

FIREPLACE.

1,419,810.

Specification of Letters Patent. Patented June 13, 1922.

Application filed August 16, 1919. Serial No. 317,995.

To all whom it may concern:

Be it known that I, ERNEST BRAMMER, residing at Victoria, in the Province of British Columbia and Dominion of Canada, have invented new and useful Improvements in Fireplaces, of which the following is a specification.

This invention relates to hot water heating systems, wherein the heat from a fire-
10 place is utilized to heat the water.

The maximum percentage of heat of a fireplace passes up through the chimney, and is consequently wasted. This heat being mixed with smoke cannot be used through
15 conveyance elsewhere and any attempt to do so would probably destroy the draught which is the first essential of a fireplace.

The heat however can be used to heat water, which is one of the most practical
20 conveyers of heat known at the present time, the water being conveyed by pipes through radiators in different parts of the building.

It is therefore the purpose of this invention to provide a water back designed to be
25 conveniently arranged in the fireplace, and whose capacity is supplemented by its connection with heating coils arranged within the chimney immediately above the water back and from which the water is conveyed
30 to the radiators in the different parts of the building.

The nature and advantages of the invention will be better understood when the following detail description is taken in connection with the accompanying drawings, the invention residing in the construction, combination and arrangement of parts as claimed.

In the drawings forming part of this specification like numerals of reference indicate similar parts in the several views and wherein:

Figure 1 is a front elevation of a fireplace.

Figure 2 is a vertical sectional view there-
45 through showing the water back and coil in position therein.

Figure 3 is an enlarged view of the water back.

Figure 4 is a fragmentary view of a ver-
50 tical coil.

Figure 5 is a view of a horizontal coil.

Referring to the drawings in detail, A indicates generally a fireplace of usual construction wherein the back wall rises vertically for a short distance as at 10 and then inclines forward a short distance for the

purpose of throwing a portion of the heat into the room, as at 11 is then inclined rearwardly as at 12 and then continues in a vertical plane through the chimney proper. 60

In accordance with the present invention, wherein it is desired to utilize the heat of the fireplace, which otherwise is wasted in passing through the chimney, I employ a water back 15 arranged within the fireplace 65

A and of a width equal to the similar dimension of the fireplace. The water back consists of the angularly disposed portions or sections to conform to the shape of the back wall as clearly shown in Figure 2. By reason of this construction, the water back may be arranged over the obtuse angle of the back wall of the fireplace, in close proximity to the latter. The heating capacity of the water back is supplemented by its connection with the heating coil 16, which is disposed within the chimney proper immediately above the water back as illustrated. 70

Either a vertically disposed or horizontally arranged coil such as disclosed in Figures 4 and 5 can be used in conjunction with the water back and in either instance the coils are detachably associated with the water back to facilitate installation or removal of said parts from the fireplace. One 80

end of the coil projects through the chimney and is adapted to be coupled with suitable supply pipes leading to the radiators in different parts of the building. The point in height to which the coil would extend of 90

course depends upon the size of the house to be heated, but in no case would the coil extend above the ceiling of the room wherein the fireplace is arranged. The dimensions of the coil in width and length would be sufficiently less than the dimension of the chimney to allow for convenience in the installation of or removal of parts from the chimney. The coil by preference is ar- 95

ranged horizontally, as shown in Figure 100 2 in order to lessen the extent of the coil and to keep it as low as possible where the heat intensity is greater. The rows of piping constituting the coil are also spaced apart, and spaced from the walls of the chimney a sufficient distance so as not to impede or retard the draught, most essential in fireplaces. Manifestly, this form of fireplace, could be used in the country wherever there is sufficient water pressure to fill 105 the water back, coil and radiators. Its use would be appreciated by lovers of fireplaces 110

everywhere; its cost would be much less than that of the hot water furnace; and it would save in fuel nearly the entire amount which the hot water furnace or any kind of furnace would consume.

The water back may be supported in the fireplace in any suitable manner, providing it is spaced from the back wall of the fireplace to allow the heat to completely envelop the water back. If desired, eye bolts 18 may be driven into the rear wall of the fireplace and suitable lugs 19 carried by the adjacent wall of the water back to be positioned within the eyes of said bolts. This permits of the water back being readily and easily installed or removed from the fireplace as the occasion requires. It is also preferred to have the front and rear walls of the water back fluted or corrugated to present a maximum heating surface, and also to form channels for the heat waves. With the water back and coil positioned within a fireplace in the manner illustrated, a saving in cost of construction and also in fuel is effected in comparison with a hot water furnace in homes of moderate size.

While I have shown and described what I consider the preferred embodiment of the

invention, I desire to have it understood that I do not limit myself in this connection, 30 and that such changes may be resorted to when desired as fall within the scope of what is claimed.

What I claim is:—

A heater for a fireplace wherein the back 35 wall has a forwardly inclined portion which merges into a rearwardly inclined portion, said heater including a water back of a width substantially equal to the width of said rear wall and having closely associated 40 walls, said water back including two angularly disposed portions defining an obtuse angle between the same, one of said portions being equal in area to the forwardly inclined portion of said rear wall, and said 45 other portion being equal in area to the rearwardly inclined portion of said wall, means for supporting the water jacket upon said inclined portions in a manner whereby said jacket is equi-distantly spaced from the wall 50 throughout its length, and a coil disposed above the water jacket and detachably associated therewith.

In testimony whereof I affix my signature.

ERNEST BRAMMER.
